OF NEW YORK.

ROLLING WINDOW-SCREEN.

1,387,452.

Specification of Letters Patent. Patented Aug. 16, 1921.

Application filed December 3, 1917, Serial No. 205,013. Renewed January 11, 1921. Serial No. 436,613.

To all whom it may concern:

Be it known that I, JOHN J. CHAPIN, of Rochester, in the county of Monroe and State of New York, have invented certain new and useful Improvements in Rolling Window-Screens; and I do hereby declare the following to be a full, clear, and exact description of the same, reference being had to the accompanying drawings, forming a part of this specification, and to the reference characters marked thereon.

This invention relates to screens of the class which are permanently fitted to window frames or other openings of buildings, and having a flexible screen adapted to be rolled within a casing or housing provided preferably at the top of the window.

The invention has for its principal object to provide a rolling window screen having side guides for the unrolled screen and clamps therefor concealed within the guides, thereby assuring a pleasing finish to the whole screen structure and avoiding unsightly accumulations of dust upon or within the screen fittings or mountings.

A further object is to provide a simple, and practical rolling screen which may be inexpensively made and applied and is efficient and durable in use, and which 30 clamps the screen edges easily and securely without interfering with the free opening or closing or convenient cleaning of the window sashes. To these and other ends the invention consists in certain improvements 35 and combinations of parts all as will be hereinafter more fully described, the novel features being pointed out in the claims at the end of the specification.

In the drawings:

40 Figure 1 is an elevation of a window casing showing one of the improved rolling screens as viewed from the inner side and shown unrolled or extended for use;

45 Fig. 2 is a vertical sectional view taken on the line 2^a—2^a in Fig. 5, with the screen rolled up as when out of use;

Fig. 3 is a rear perspective view of an intermediate portion of one of the side screen guides;

50 Fig. 4 is an enlarged horizontal sectional view taken on the line 4^a—4^a in Fig. 1;

Fig. 5 is a detail sectional view taken on the line 5^a—5^a in Fig. 2, showing the screen edge unclamped;

55 Fig. 6 is a detail sectional view showing the screen edge clamped in its guide;

Fig. 7 is an exterior view of a window showing the screen fully extended;

Fig. 8 is a vertical section taken on the irregular line 8^a—8^a in Fig. 1, and

Fig. 9 is a detail rear sectional perspective view of the lower clamp bearing block in the right hand screen guide.

Similar reference characters in the several figures indicate the same parts.

The numeral 1 indicates the flexible screen, preferably made of wire netting, secured at one end to a spring roller 2, which is journaled at its ends in brackets 3, located above an opening 4, such as a window bounded by 70 a suitable casing or frame 5, in which may be fitted one or more glazed sashes, a portion only of the upper outer sash 6 being shown in Fig. 4. The roller is preferably concealed within a casing or housing 7 which 75 also protects it. The free end of the screen passes downwardly through an opening 8 in the frame 5, and is attached to and within a U-shaped transverse binding or clamping strip 9 which locks this end of the screen 80 within a dovetail shaped slot 10 formed in the inner wall of a hollow transverse screen bottom rail 11. The latter is preferably molded or rolled from sheet metal, and at its ends is closed by blocks 12, 12, shown in 85 Figs. 1, 4 and 7. These blocks are slotted vertically at their outer edges which are guided upon the laterally projecting inner flange portions 14 of hollow metal guides at the sides of the window frame 5, which also 90 comprise the inner wall 15 and a connecting wall 16. Each of the guides is secured at its ends, by screws 17, to the face of the outer sash stop, or rail 18 of the window casing so that the guide flanges 14, extend laterally 95 inwardly toward each other. In this position the guides hold the screen close to the window sash and do not interfere with the closing of the shutters or blinds which may be fitted within the casing 5. There may be

one or more intermediate screw fastenings 19 for each guide, depending upon its length, as shown in Figs. 1 and 2. These screws 19 are set into the frame portion 18 before the guide is applied thereto, the screw heads 100 standing off from the frame sufficiently to snugly receive beneath them the narrow base wall 16 of the guide which is transversely slotted at 20 to receive the body or stem of the screw, the head of which passes laterally 105 through a curved slot 21 made in the inner side wall 15 of the guide. The communicat-

ing guide slots 20, 21 are shown in Fig. 3. The guide wall 15 is curved at its edge toward the rear flange 14 and stands off from the latter sufficiently to provide between them a vertical groove or channel 22 in which moves one edge of the screen. Fitted within the ends of the guides are short upper and lower bearing blocks 23 having transverse openings through which pass screws 17 or other securing devices, which thus firmly support the blocks while also holding the guide to the window frame, and the bearing blocks reciprocally impart necessary strength to the guide to resist all strains incident to tightening of the screws 17.

An important feature of construction consists in inclosing the screen edge clamps within the screen guides to assure a more neat and pleasing finish to the guides and the clamps and to the whole screen structure, and also to avoid unsightly and not easily removed dust accumulations, than prevails when the clamps are arranged outside of the guides and more or less in full view. In this constructive feature the screen clamps inclosed in the guides may have any desired form and mode of operation, but it is preferred to form the clamps of a rod extending for practically the full length of the guides. The clamping rod, indicated by 24, has at its opposite ends journals 25 fitted in recesses in the opposed lower and upper faces of the respective upper and lower blocks 23, preferably nearer the outer ends of the blocks and in such relative positions as to cause the rod, when turned from the inoperative position, shown in Fig. 5, to that shown in Fig. 6, to bind throughout its entire length upon the inner surface of the wall 15, near its strong laterally curved edge, whereby the clamp rod 24 and both the inside and outside walls 14 and 15 of the guide coact to mutually brace each other while the edge of the screen 1 is clamped by the rod against the outer flange 14. A further improvement consists in forming the screen clamping rod in a manner assuring its action gradually lengthwise upon the screen edge. This is conveniently accomplished by making the rod of a flat bar, with rounded edges and imparting thereto a lengthwise twist, or a partial turn from end to end, as shown in Figs. 2, 5 and 6, which causes the rod when rotated to exert its clamping action gradually upon the screen edge from one end portion of the screen to the other, thus making the manual operation of the screen clamps easier and more certain and bringing less strain upon the screen material than occurs when the screen edge is clamped simultaneously along its whole length. For turning the clamp rod 24, a drop handle 26 is provided having an end tongue 27, movably fitting within a vertical groove in the outer end of a hori-

zontal stud 28, fixed in the clamping rod 24, and coupled to the stud by a pivot pin 35.

When assembling the parts the clamp rod 24 with its fixed stud 28 is first slipped endwise into the hollow guide, and the rod 70 adjusted to project its stud 28 outwardly through a slot 29 in the wall 15, as shown in Figs. 1 and 8, whereupon the end bearing blocks 23 are inserted in the guide and engaged with the rod bearings 31, and after 75 the guide slot 20—21 is engaged with the previously fixed intermediate fastening screw 19, the opposite end fastening screws 17 are applied laterally through the apertures in the guide and the bearing blocks 80 23, to fasten the whole structure to the part 18 of the window frame 5. The drop handle 26 may now be coupled to the stud 28 by the pin 35, and will normally depend in front of the screen guide. 85

When the screen 1 is drawn downwardly in its two guide channels, the handles 26 will be raised horizontally and will then be turned about one-quarter around toward the screen, as shown in Figs. 1 and 6, thereby 90 causing the rods 24 to securely clamp the opposite edges of the screen against the guide flanges 14. The handles being then released drop to a vertical position at the inner edges of the guides. Whether the 95 screen 1 be drawn downwardly and clamped, or unclamped and rolled upon the roller 2, the drop handles 26 are practically the only visible portion of the screen clamping mechanism and they present a pleasing 100 appearance in keeping with the appearance of the clamp concealing guides, without marring the architectural symmetry of the window design or trimmings.

It will also be noticed that by concealing 105 the screen edge clamps 24 within the guides, the nature of the screen clamping mechanism is not readily apparent because of the lateral projection of the guide flange 14 beyond the inside wall 15 so that an intruder would find it difficult to pry the clamps loose from the outside of the window without destroying the screen, hence this invention permits 110 keeping the window sashes open for ventilation while providing a substantial measure 115 of protection against the unlawful entrance of an intruder. As an additional locking device the bottom rail 11 of the screen carries on each of its end blocks 12 a latch 30 pivoted to a lug 31, and having a hook end 120 39 adapted to automatically lock into the recess 32, made at the lower end of the edge of each guide flange 14, as shown in Fig. 1 of the drawings. The latches 30 swing 125 outwardly at their lower ends and about at right angles to the face of the screen, and their inner plate portions preferably range about parallel with the screen and may be used as convenient finger grips in manipulating the screen. 130

The rotation of the engaging edges of the clamping bars or rods 24 is in a direction outwardly toward the screen to move its edges into contact with the guide flanges 14 and 5 also laterally thereof, thus tending to draw the edges of the screen outwardly in opposite directions to stretch it with sufficient tension to cause it to lie flat over the entire opening and prevent it from bulging. In 10 this position one edge of each clamping rod is in engagement with the curved edge of the inner flange 15 which serves as a bearing or brace to stiffen the rod throughout its length and resist any tendency of the 15 rod to buckle if pressure is applied transversely of the screen.

I claim as my invention:

1. An edge clamp for window screens comprising a hollow channel member having 20 opposed walls and a clamping member located between them and adapted to be rotated to engage the wall at one side of the member and to clamp a screen against the other wall at the other side of the member.

2. An edge guide for screens comprising a clamping surface and a rotatable clamping member having a spiral edge and positioned to coöperate with said surface and clamp a screen edge against it.

3. An edge guide for screens comprising a channel member having two spaced surfaces, the face of one surface being bent toward the other, spaced bearings within the member and a rod journaled at its ends in 35 the bearings and having two longitudinal edges, one coöperating with each of said surfaces of the channel.

4. A hollow guide for a rolling window screen, comprising an outside wall, an inside 40 wall, and a connected attaching base portion, said inside wall being rounded over at its inner edge toward the outside wall and spaced therefrom to provide between them a channel adapted to receive one edge of 45 the screen, and a clamping member located within the guide adjacent the rounded edge of the inside wall and having portions thereon coöperating with both walls.

5. A hollow guide for a rolling window 50 screen, comprising an outside wall, an inside wall, and a connected attaching base portion, said inside wall having its edge bent toward the outside wall and spaced therefrom to provide between them a channel adapted to 55 receive one edge of a screen, said outside wall being wider than the curved inside wall to provide beyond it a laterally projecting protective flange, a rotatable clamping member in the guide and an operating handle therefor arranged to occupy a position between the outer edges of the two walls when the clamping member is in one position of adjustment.

6. The combination with a rolling window

screen, of a side guide having a channel for 65 receiving one edge of the screen and extending substantially the length of the screen, and a clamping rod pivoted therein and adapted when rotated to clamp the edge of the screen to a wall of the guide throughout 70 the length of the latter, a stud projecting outwardly from the rod, and an operating handle on the stud.

7. An edge clamp for screens comprising a hollow channel member for receiving one 75 edge of a screen and including parallel walls, and a rod pivoted within said member and having a spiral engaging surface shaped to clamp gradually lengthwise upon the screen when rotated.

8. A rolling window screen fixture comprising oppositely disposed hollow side edge guides having a channel receiving one edge of the screen, and a rod pivoted within each 85 guide and twisted to provide a spiral surface which acts gradually lengthwise upon the screen to clamp it within the guide, and means for turning the rod.

9. In a rolling window screen fixture, the combination with a window frame and a 90 roller carrying a screen adjacent said frame, of hollow guides each having a channel receiving one edge of the screen located at opposite sides of the frame, bearing blocks inclosed within each guide at each end 95 thereof, screen clamping rods journaled, inclosed in the guides and in said blocks, means for turning the rods, and fastening devices passing laterally through the guides and their bearing blocks and securing them to 100 the window frame.

10. In a rolling window screen, the combination with a window frame and a roller carrying the screen located at one side of 105 said frame, of opposite hollow guides each having a channel receiving one edge of the screen and provided with a slide extending in a direction transversely of the window opening, blocks within the ends of each guide and forming opposing bearings, screen 110 clamping rods journaled on the blocks within the respective guides, operating members extending through the slots of the guides for turning the inclosed clamping rods, and fastening means passed laterally through the 115 guides and bearing blocks and securing said guides and blocks to the window frame.

11. In a window screen fixture, the combination with a screen and a guide for its edge comprising a narrow inner wall and 120 a spaced wider outer wall projecting laterally inward beyond the inner wall and having a notch, of a screen bottom rail movable along the projecting outer guide wall and a latch pivoted on the bottom rail 125 and having a portion adapted to enter said notch to lock the screen.

JOHN J. CHAPIN.
